[57] CLAIM

The ornamental design for a can compactor, as shown and described.

DESCRIPTION

FIG. 1 is a perspective view of a can compactor showing my new design in a closed position;

FIG. 2 is a top view thereof in the closed position;

FIG. 3 is a bottom view thereof in the closed position;

FIG. 4 is a rear view thereof in the closed position;

FIG. 5 is a front view thereof in the closed position;

FIG. 6 is a left side view thereof in the closed position;

FIG. 7 is a right side view thereof in the closed position;

FIG. 8 is a perspective view thereof during its movement between the closed position and an open position;

FIG. 9 is a perspective view thereof in its open position;

FIG. 10 is a top view thereof in the open position;

FIG. 11 is a bottom view thereof in the open position;

FIG. 12 is a left side view thereof in the open position;

FIG. 13 is a right side view thereof in the open position;

FIG. 14 is a front view thereof in the open position; and,

FIG. 15 is a rear view thereof in the open position.
